Attorney.

UNITED STATES PATENT OFFICE.

Received on the 25th day of January, 1916, and recorded in the Office of the Commissioner of Patents, as follows:

LOUIS MAYER AND EDWIN A. BYE, of Mankato, Minnesota, assignors to MAYER & BROTHERS COMPANY, of Mankato, Minnesota, a corporation of Minnesota.

Combined Fan and Pump for Self-Propelled Vehicles.

Serial No. 1,206,787. Filed February 19, 1916. Specified of Letters Patent. Patented Nov. 28, 1916.

Application filed February 19, 1916. Serial No. 79,300.

To all whom it may concern:

Be it known that we, LOUIS MAYER and EDWIN A. BYE, citizens of the United States, residing at Mankato, in the county of Blue Earth and State of Minnesota, have invented a new and useful Improvement in Combined Fans and Pumps for Self-Propelled Vehicles, of which the following is a specification.

An object of this invention is to unify the construction of farm tractors and self-propelled vehicles, this invention pertaining more particularly to the unification of the fan and pump which are commonly employed in connection with tractors which are driven by gas power.

The advantageous results obtained by this invention are primarily, simplicity of construction, reduction of cost and the production of mechanism which is less liable to disorder than in prior devices.

Another advantage attained is the strengthening of the parts with less material than heretofore.

In the accompanying drawing forming part of this specification, Figure 1 is a side elevation of a detail of a gas tractor, illustrating our invention, parts of the structure being broken away to more clearly expose the mechanism; Fig. 2 is a front elevation of part of the structure illustrated in Fig. 1, and Fig. 3 is a central vertical section through the structure illustrated in Fig. 2.

In the drawing 2 and 3 indicate a pair of longitudinal channel members forming part of the frame or body of a tractor on which is secured the usual radiator 4 supplied with water or other cooling medium through

the circulating pipes 5 and 6, said radiator being arranged on the front end of the body. Distanced from the front end of the body is the usual gas engine 7 or other prime mover having a crank shaft 8 extending longitudinally in a forward direction of the body from the crank casing 9.

Secured to the side members 2 and 3 of the body, such as by means of bolts 10 is a stand 11, the lateral ends of which rest upon the side members and the central or body portion of which projects upwardly midway of said ends and forms a socket 12 in which a fan shaft 13 is bolted and forms a journal support for the fan 14. This fan

is arranged immediately back of the radi-

ator, so that as it revolves, it propels air through the radiator for cooling purposes in the usual manner.

The body of the stand is formed with a circular pump chamber 15, which is closed by a cover 16 secured thereto such as by bolts 17. The pump chamber contains the impelling element 18, which is mounted upon a shaft 19, said shaft being coupled at 20 to the end of and in alinement with the crank shaft 8 to form a revoluble extension thereof. The shaft member 19 is held in fluid tight connection with the pump chamber by the glands 21 and 22 respectively on the body of the pump chamber and on the cover element 16. The forwardly projecting end of the shaft element 19 adjacent the gland 21 carries a belt pulley 23 alined with a corresponding belt pulley 24 integral with the fan 14 and journaled upon the fan shaft 13. A belt 25 passing over the pulleys 23 and 24 serves to transmit motion from the shaft 19 to the fan driving the latter at suitable speed for cooling purposes.

The body of the stand containing the pump chamber 15 is formed with an outlet duct 26, which is connected with the pipe 6 leading backwardly to the engine in the usual manner for circulating water or other cooling medium through the usual jacket compartments in the engine casing. The cover 16 is also formed with an inlet duct 27, which is connected with the pipe 5 leading forwardly to the radiator 4. In operation as the shaft 19 is revolved by the crank shaft of the engine, the impelling element of the pump and the fan are revolved simultaneously at suitable speed. Freely hung from the shaft 13 is a link 28 carrying an idle pulley 29, the latter bearing by its periphery upon the belt 25 and holding the latter sufficiently tight to engage the pulleys and prevent slipping. The entire apparatus being composed of a minimum number of parts minimizes expense in construction and liability of the parts getting out of alinement. The stand 11 may be of skeleton form and of angle construction for the purpose of saving material without impairing strength.

In accordance with the patent statutes, we have described the principles of operation of our invention together with the apparatus which we now consider to repre-

sent the best embodiment thereof, but we desire to have it understood that the construction shown is only illustrative, and that the invention can be carried out by other means and applied to uses other than those above set forth within the scope of the following claims.

Having described our invention what we claim as new and desire to protect by Letters Patent is:

1. Apparatus of the class set forth, comprising, in combination, a vehicle body frame, an engine mounted upon said frame having an extending crank shaft, a radiator mounted upon said frame, a stand secured to said frame having a fan journaled thereon adjacent said radiator and formed with a pump chamber in its body, an impelling element arranged in said pump chamber, a shaft carrying said impelling element journaled in the body of said stand and coupled to said crank shaft and a drive connection between the shaft carrying said impelling element and said fan, said pump chamber being formed with inlet and outlet ducts for the purposes specified.
2. Apparatus of the class set forth, com-

prising, in combination, an engine having an extending crank shaft, a radiator, a frame upon which said parts are mounted, a stand secured to and reinforcing the strength of said frame having a body formed with a pump chamber and an upwardly extending support, a fan journaled upon said support to impel a current of air through said radiator, an impelling element journaled in said pump chamber and coupled to said shaft to be driven thereby and a drive connection between said fan and said impelling element.

3. In apparatus of the class set forth, a stand having laterally extending arms, a centrally disposed upwardly projecting support and a pump chamber, a drive shaft extending through said support, an impelling element mounted upon said shaft, a fan journaled upon said support, a drive connection between said shaft and said fan and means for revolving said shaft.

In testimony whereof, we have signed our names to this specification.

LOUIS MAYER.
EDWIN A. BYE.
